INVENTOR:

J. F. Low

BY

E. J. Fletcher-Hough

UNITED STATES PATENT OFFICE.

JAMES FLEMING LOW, OF TORONTO, ONTARIO, CANADA.

VACUUM-CONTROL MECHANISM FOR PULP-MOLDING MACHINES AND THE LIKE.

Application filed October 31, 1927. Serial No. 230,021.

This invention relates to a vacuum control mechanism for pulp molding machines and the like, as described in the present specification and illustrated in the accompanying drawings which form part of same.

The invention consists essentially of the novel features pointed out broadly and specifically in the claims for novelty following a description containing an explanation in detail of an acceptable form of the invention.

The objects of the invention are to provide a very efficient control mechanism controlling the flow or displacement of a fluid from one part of a machine to another, where one of such parts is fixed and the other is movable; to especially adapt such a control chamber to machines requiring the maintaining of a partial vacuum in one or more of its functional parts; to reduce wear and leakage to a minimum; to easily replace the parts subjected to wearing and to reduce the number of such wearing and rubbing parts to a minimum; and generally, to improve upon known control chambers.

In the drawings, Figure 1 is a sectional view of a chamber built in accordance with this invention.

Figure 2 is an end view of a shaft shown in Figure 1.

Figure 3 is a fragmentary perspective view of the shaft.

Figure 4 is a perspective view of the casting or casing shown in Figure 1.

Figure 5 is a perspective view of the wax washer.

Like numerals of reference indicate corresponding parts in the various figures.

Referring to the drawings, 10 is a rotatable member of a machine (not shown), 40 this member taking the form of a hollow shaft 11 having rigid therewith a plug-like portion 12 extending into the reduced portion 13 which turns in suitable bearings (not shown). The form of the invention as here- 45 in disclosed is taken from a pulp molding machine, an application for a patent of which machine was filed on the 16th day of December, 1926, as serial No. 155,306, and reference to the specification forming part 50 of that application is invited as illustrating a specific practical application of this present invention.

A number of pipes 14 are led from a functional part of the machine (not shown)—say suction dies such as disclosed 55 in the said application, Serial No. 155,306,

which require the application of a vacuum to cause a layer of pulp substance to be deposited upon their molding face—to the outer end face 15 of the plug-like portion 12. 60 The pipes 14 are passed through the holes 15A in the portion 12 and have their ends threaded as at 17 to receive suitable nuts 18 which fit into depressions 19 counterbored into the end face 15. The depressions are 65 made deep enough to allow a clearance between the face 15 and the nuts. It will be manifest that the function of these nuts is to rigidly secure the pipes in position.

20 is a flat disc of wax or other suitable 70 material made to a diameter approximately equal to that of the portion 12 and fitting over the reduced portion 13, and having ports 21A therethrough spaced to be in alignment with all of the pipes 14 when any one 75 of said pipes is in alignment with any one of said ports.

20A is a metal disc perforated in the centre and fitting over the reduced portion 13; the disc carries the pipes 21 on the outer ends of 80 which are fastened to the flexible tubes 22; the flexible tubes are connected to pipes leading to suitable vacuum producing means or to the atmosphere. The pipes 21 are threaded into the disc 20A and are spaced to be in alignment with the pipes 14 when any one of the latter pipes is in alignment with any one of the former pipes; suitable nuts 23 are screwed onto the threaded ends of the pipes 21, fitting into depressions 24 counterbored into said disc. The depressions 24 are made deep enough to allow a clearance 90 between the face of the metal disc and the nuts 23.

25 is a metal casing or cap sized at the 95 open end to slidably engage the outer end of of the hollow shaft 11 and having the end wall 26 perforated at 27 to form a clearance or a passage for the reduced portion 13 of the shaft 10. The casing 25 is locked against 100 rotation and lateral and longitudinal movement by any suitable means, as with projections 28 bearing in or engaging corresponding depressions in a detachable bracket (not shown) secured to a fixed or rigid part 105 of the machine mounting the rotatable shaft 10, or as more particularly described in the said application filed as Serial No. 155,306. The end wall 26 of the casting 25 is also perforated at 27A to form a clearance for the passage of the pipes 21.

30 are springs encircling the pipes 21 and

compressed between the wall 26 of the casting 25 and the slideable disc 20A, so that the springs normally urge the disc toward the face 15 of the plug-like portion 12. As the 5 wax washer 20 is to be secured against rotation and also secured in a predetermined position relative to said disc 20A, namely, so positioned that its ports 21A are in alignment at all times with the pipes 21, suitable 10 means are provided, such as dowel pins 31 rigidly secured to the disc and projecting into the wax washer 20. As the shaft 10 rotates and the wax washer gradually wears down, the compressed springs 30 gradually 15 shift the disc 20A toward the wax washer.

In order to prevent dust from penetrating into the chamber and to make a tighter joint between the casting 25 and the hollow shaft 11, the shaft is provided with a shoulder 33 20 cut into its edge; a wax washer or ring 34 is sized to fill in the space formed by the shoulder, as best shown in Figure 1.

35 are depressions or chambers made into the face of the wax washer running from a number of ports 21A and extending partly or completely between a number of these ports, according to the co-operation desired between and the functions required of each or all the ports or more particularly the 30 pipes 21.

As there is a partial vacuum within some of the chambers 35 and the depressed holes while the empty space within the casing 25 is opened to the atmosphere, a pressure is 35 created which exerts a force on the disc 20A independent of that exerted by the compressed springs 30.

Operation: As the shaft 10 rotates while the wax washer, the metal disc and the 40 casing remain fixed and each of the pipes 14 is successively brought into alignment with the several pipes 21, each pipe line 14 thus being subjected to varying prearranged vacuum conditions. When the wax washer 45 or wearing or rubbing part 20 is worn down, the casing is removed and a fresh washer put in. The use of wax reduces the wear upon the rubbing parts, tends to lubricate, and is a substance very well suited for such 50 machines as those to which this present invention is applicable.

What I claim is:

1. In a vacuum control mechanism for pulp molding machines and the like, a rotatable shaft formed with a shoulder to provide a reduced end for journaling in a bearing, a non-rotatable casing mounted adjacent the reduced end of said shaft and forming therewith a cylinder-like compartment, passages in said shaft for connection with a functional part of the machine mounting said shaft and opening into said compartment, a non-rotatable washer slideable in said compartment, a disc of soft material removably secured to one face of said

washer and engaging said shoulder, said disc having ports therethrough spaced for registering with said passages and depressed to connect a number of said ports, pipes carried by said washer in alignment with said ports and projecting through the casing for operative connection with apparatus, and compressed springs urging said disc towards said shoulder.

2. In a vacuum control mechanism for pulp molding machines and the like, a rotatable shaft formed with a shoulder to provide a reduced end for journaling in a bearing, a non-rotatable casing mounted adjacent the reduced end of said shaft and forming therewith a cylinder-like compartment, pipes in said shaft for connection with a functional part of the machine mounting said shaft and opening through said shoulder, a non-rotatable washer slideable in said compartment, a disc of soft material removably secured to one face of said washer and engaging said shoulder, said disc having ports therethrough spaced for registering with said pipes and depressed to connect a number of said ports, pipes carried by said washer in alignment with said ports and projecting through the casing for operative connection with apparatus, and compressed springs encircling said last-mentioned pipes and urging said disc towards said shoulder.

3. In a vacuum control mechanism for pulp molding machines and the like, a rotatable shaft formed with a shoulder to provide a reduced end for journaling in a bearing and having said shoulder counterbored to form nut recesses, a non-rotatable casing mounted adjacent the reduced end of said shaft and forming therewith a cylinder-like compartment, horizontally-arranged pipes carried by said shaft for connection at one end with a functional part of the machine mounting said shaft and terminating at the other end in said nut recesses, nuts threaded onto said pipes, a non-rotatable washer slideable in said compartment, a disc of soft material removably secured to one face of said washer and engaging said shoulder, said disc having ports therethrough spaced for registering with said pipes and depressed to connect a number of said ports, pipes carried by said washer in alignment with said ports and projecting through the casing for operative connection with apparatus, and compressed springs urging said disc towards said shoulder.

4. In a vacuum control mechanism for pulp molding machines and the like, a rotatable tubular shaft having a plug-like reduced portion rigidly secured thereto at one end thereof forming a journal, a non-rotatable casing mounted adjacent the reduced end of said shaft and forming therewith a cylinder-like compartment, passages through said plug-like portion for connection with a
